UNITED STATES PATENT OFFICE.

EUGENE J. McCARTY, OF CLINTON, MASSACHUSETTS.

DESIGN FOR SKIRT-BINDING.

SPECIFICATION forming part of Design No. 31,024, dated June 13, 1899.

Application filed April 19, 1899. Serial No. 713,693. Term of patent 7 years.

To all whom it may concern:

Be it known that I, EUGENE J. McCARTY, a citizen of the United States, and a resident of Clinton, in the county of Worcester and Commonwealth of Massachusetts, have invented and produced a new and original Design for a Skirt-Binding, of which the following is a specification, reference being had to the accompanying drawings, forming a part thereof.

The leading feature of my design consists in a durable skirt-binding presenting a head having a brush on the upper and lower edges thereof, the face view having the fabric raised and cut, representing a velvet surface.

Figure 1 represents a face view of a piece of skirt-binding embodying my design. Fig. 2 is a view in rear elevation. Fig. 3 represents a sectional view.

In the drawings, A designates a piece of skirt-binding consisting of head B, with the

brushes C on the upper and lower edges thereof. On the face view of the head the fabric D is raised, as by jacquard, and cut, giving a velvet surface thereof. The rear elevation of head presents a plain weave E. The sectional view presents the fabric D joined to the weave E by threads F.

Having described my invention, what I claim as new, and desire to secure by Letters Patent, is—

The design for a skirt-binding substantially as shown and described.

In testimony that I claim the foregoing as my invention I have signed my name, in presence of two witnesses, this 8th day of April, A. D. 1899.

EUGENE J. McCARTY.

Witnesses:

EDMOND A. EVANS,
ALFRED L. POWELL.
